UNITED STATES PATENT OFFICE.

WILLIAM R. WATROUS, OF CHESTER, CONNECTICUT, ASSIGNOR TO C. J. BATES & SON, A FIRM COMPOSED OF CARLTON J. BATES AND HAMILTON C. BATES, OF CHESTER, CONNECTICUT.

MANICURE IMPLEMENT.

1,312,653.

Specification of Letters Patent.

Patented Aug. 12, 1919.

Application filed February 1, 1918. Serial No. 214,829.

To all whom it may concern:

Be it known that I, WILLIAM R. WATROUS, a citizen of the United States, residing at Chester, in the county of Middlesex and 5 State of Connecticut, have invented a new and Improved Manicure Implement, of which the following is a specification.

My invention relates more especially to the class of implements commonly known 10 as emery boards, and an object of my invention, among others, is to provide such an implement of this kind that shall be extremely convenient in use and that shall embody a plurality of emery boards so constructed 15 that they may be conveniently renewed from time to time.

One form of implement embodying my invention and in the construction and use 20 of which the objects herein set out, as well as others, may be attained, is illustrated in the accompanying drawings, in which—

Figure 1 is a side view of my improved 25 implement, showing one of the emery boards extended for use and the others partially opened out.

Fig. 2 is an edge view showing the emery boards disconnected from the handle.

Fig. 3 is a detail view, scale enlarged, on 30 plane passing laterally through the implement and through the axis of the emery boards.

In the accompanying drawings the numeral 5 indicates the handle of my improved implement, that is preferably made from 35 some resilient material, as celluloid or the like, such handle being of U-shape in cross section and having an opening 6 at one end and a lip 7 partially closing its opposite end, the front edge being open. Pivot studs 40 8 are secured preferably to each of the side parts near the open end 6, these studs, in the structure herein shown, being headed, as by riveting, to secure them in place. They extend inwardly a short distance only, leaving a space 9 between their inner ends.

A number of emery boards or blades 10 are pivotally secured together so that they may be separately swung upon their pivots.

This pivot preferably embodies a pivot sleeve 11 passing through the boards or 50 blades and having flanges or heads 12 at its ends to permanently secure the boards to the pivot sleeve, that is, so that said sleeve and boards may be removed with the latter in place on the sleeve. 55

These boards are of a thickness, and the sleeve is of a length greater than the space 9 between the inner ends of the studs and the side parts 12 of the handle will, therefore, be required to be sprung apart sufficiently to enable the sleeve to be placed upon the studs 8, the latter projecting a short distance into the ends of the sleeve when the force required for springing the sides apart is released, the normal position 60 being shown in Fig. 3 of the drawings. 65

It will be seen from my improved construction that a number of blades are provided which may be successively used as they are all worn out, and when they have 70 been worn out a new set may be readily inserted in place in the handle.

In accordance with the provisions of the patent statutes, I have described the principles of operation of my invention, together with the device which I now consider to represent the best embodiment thereof; but I desire to have it understood that the device shown is only illustrative, and that the invention may be carried out 80 by other means. 75

I claim:—

1. An implement comprising a handle having resilient side parts, a pivot, and a plurality of blades secured to said pivot irrespective of said handle and for separate pivotal movement thereon, said handle and pivot being constructed to removably secure the pivot through the agency of the resiliency of the side parts of the handle. 85 90

2. An implement comprising a handle having resilient side parts, a pivot embodying sockets at each end thereof, means upon the handle to enter said sockets to removably secure the pivot in place, and a plurality of blades permanently mounted on 95

the pivot irrespective of said handle and for separate pivotal movement thereon.

3. An implement comprising a handle having resilient side parts, a pivot embodying sockets in opposite ends thereof, studs upon the resilient side parts to enter said

sockets to removably secure the pivot in place, and a plurality of blades mounted on said pivot and permanently secured thereto independently of and apart from said handle.

WILLIAM R. WATROUS.
